(57) **CLAIM**

The ornamental design for a children's gaming camera, as shown and described.

DESCRIPTION

FIG. 1 is a front perspective view of a children's gaming camera showing my new design;

FIG. 2 is a back perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the encircled portion shown in FIG. 2.

The broken lines shown in the drawings depict portions of the children's gaming camera in which the design is embodied that form no part of the claimed design.

The dot-dash broken lines encircling an enlargement portion of the design forms no part of the claimed design.
